UNITED STATES PATENT OFFICE.

WILLIAM N. CAPURRO, OF HOT SPRINGS, ARKANSAS.

DESIGN FOR A SPOON.

SPECIFICATION forming part of Design No. 23,651, dated September 25, 1894.

Application filed August 21, 1894. Serial No. 520,933. Term of patent 3½ years.

To all whom it may concern:

Be it known that I, WILLIAM N. CAPURRO, a citizen of the United States, residing at Hot Springs, in the county of Garland and State 5 of Arkansas, have invented and produced a new and original Design for a Spoon; and I do hereby declare the following to be a full, clear, and exact description of the same, reference being had to the accompanying drawing, forming a part thereof.

The invention relates to a new and original design for a spoon.

The drawing is a plan view of my design.

The object of my invention is to provide a 5 souvenir spoon of new and pleasing design.

In the drawing A is the bowl, of heart shape, the interior walls of which around their edges are so ornamented as to leave an irregular heart shaped space a in the center suitable 10 for an inscription or name.

B is the spirally twisted stem or shank sur-

mounted by a circular band or shield b open on the top within which is supported a representation of a rabbit's foot C which forms the outer and wide end of the handle.

25

The essential feature of my design is a spoon having a heart shaped bowl, an irregular heart shaped space within said bowl, the spirally twisted stem surmounted by a circular band or shield and a representation of a 30 rabbit's foot supported within said band or shield and forming the outer and wide end of the handle.

What I claim is—

The design for a spoon substantially as 35 herein shown and described.

In testimony whereof I affix my signature in presence of two witnesses.

WILLIAM N. CAPURRO.
